(57) CLAIM

The ornamental design for a tote with wheels, as shown and described.

DESCRIPTION

FIG. 1 is a top perspective view of a tote with wheels; FIG. 2 is a bottom perspective view of the tote with wheels shown in FIG. 1;

FIG. 3 is a top plan view thereof;

FIG. 4 is a bottom plan view thereof;

FIG. 5 is a right side elevational view thereof, the left-side elevational view being a mirror image thereof;

FIG. 6 is a front elevational view thereof; and,

FIG. 7 is a rear elevational view thereof.

The broken lines illustrate portions of the tote with wheels that do not form part of the claimed design.

1 Claim, 4 Drawing Sheets
